UNITED STATES PATENT OFFICE.

JAMES HORROCKS, OF MANCHESTER, ENGLAND.

MECHANISM FOR CONVERTING MOTION.

SPECIFICATION forming part of Letters Patent No. 707,112, dated August 19, 1902.

Application filed January 10, 1902. Serial No. 89,148. (No model.)

To all whom it may concern:

Be it known that I, JAMES HORROCKS, a subject of the King of Great Britain and Ireland, and a resident of Parker Street Mill, Ashley 5 Lane, Manchester, county of Lancaster, England, have invented a certain new and useful Mechanism for Converting Motion, (for which I have filed application for British Patent No. 19,202, dated September 26, 1901;) 10 and I do hereby declare the following to be a full, clear, and exact description of the invention, such as will enable others skilled in the art to which it appertains to make and use the same.

15 My said invention relates to an improved combination of mechanism for converting rotary motion into reciprocating rectilinear motion.

It is particularly advantageous for operating the traversing thread-guide device used in winding machinery; but it is also applicable to other purposes where a uniform velocity at all parts of the travel, combined with a practically instantaneous reversal of 25 the direction of motion, is required.

The accompanying drawings illustrate my said invention as applied to the operation of the thread-guides of a winding-machine.

Figure 1 is a plan. Fig. 2 is a sectional elevation on the plane A B of Fig. 1. Figs. 3, 4, and 5 are enlarged views of details to be presently explained.

The shaft 1 of Fig. 2 is the main driving-shaft of a thread-winding machine. 2 is the 35 end of the carriage which carries the thread-guides and to which a reciprocating motion is to be imparted.

A vertical shaft 3 derives continuous rotary motion through the bevel-wheels 3^a 3^b 40 from the shaft 1 and transmits it to a pinion 4, secured to the upper end of the shaft 3. The pinion rotates in the direction of the arrow w, Fig. 1.

The pinion 4 is provided with teeth on only 45 a portion of its periphery.

A sliding traverse-block 5 has internal racks 5^a 5^b, with their teeth opposed to each other and set in such relative positions as to engage alternately with the teeth of the pinion.

50 In Fig. 1 the teeth of the pinion are just commencing to engage with the rack 5^a and will drive the traverse-block 5 to the right

while the plain periphery of the pinion 4 is passing clear of the points of the teeth of the other rack 5^b. When the teeth of the pinion in their continued revolution come into engagement with the rack 5^b, the traverse-block 5 will be driven a similar distance to the left, and so on.

55 The method of obtaining a reciprocating motion from a pinion rotating between two racks is not in itself new, and I make no broad claim to such a combination.

According to my present invention I form the teeth of the pinion and of the racks at 65 the place where they first come into engagement with each other of graduated lengths. This is illustrated in Figs. 3, 4, and 5. Fig. 3 is a plan. Fig. 4 is a sectional elevation of the traverse-block 5, seen in the direction of 70 the arrow y of Fig. 3. The teeth of the rack are lettered from a to l. Fig. 5 is an elevation in the direction of the arrow x of Fig. 3. The pinion 4 is shown in full lines. The teeth of the rack, with which it is just coming into engagement, are indicated by dotted lines. The lettering of the teeth in this figure is necessarily in the reverse order to Fig. 3. The pinion 4 (see Fig. 5) is undercut at 75 4^a and 4^b, and the teeth b c d e of the rack 80 are shortened in graduated or stepped fashion, so that the stepped overhanging portions of the pinion 4^a 4^b can pass clear over them until the advancing fore edge 4^c of the pinion meets the half-tooth a of the rack when 85 the latter begins to move. The movement of the rack and the pinion now brings the fore edge 4^d of the next overhanging part against the tooth b. The half-tooth 4^e of the pinion comes next against the tooth c, and thereafter 90 the full teeth of the pinion come into successive engagement with the other teeth of the rack. Although only four stepped teeth are shown by way of example it is to be understood that this may be varied to suit the pitch of 95

the teeth and the diameter of the pinion. The object of the stepping is to enable the first operating front face 4^c of the pinion to reach the tooth a without coming into contact with the other teeth. The number of teeth on the 100 pinion and the position of the racks is so arranged that there is the least possible interval of time between the last tooth of the pinion leaving one rack and the part 4^c meeting

the tooth α of the other rack. To minimize shock on the reversal of the motion, I use buffers of rubber or other suitable material. Two of these, 6 and 7, are mounted on the rod 8, attached to and traveling with the carriage 2. The latter is connected by the rod 8^a to the traverse-block 5. A stop 9 is formed on a bracket 9^a between the buffers. In addition to these buffers for cushioning the carriage 2 I use two circular buffers 10 and 11, covered with hide or other suitable material. The circular buffers are free to rotate on the pins on which they are mounted in slotted carriers 10^a and 11^a, by means of which they may be very accurately adjusted, so as to cushion the stroke at the most suitable point. A similar circular buffer 12 is mounted on a pin on the pinion 4 and is carried around by the latter, so as to come alternately into contact with the buffers 10 and 11 just before but almost simultaneously with the contact of the part 4^c of the pinion with the rack. Owing to the circular buffers being free to rotate on their pins and the way the buffer 12 meets the buffers 10 and 11, a cushioned rolling contact or impact is produced which absorbs the momentum of the moving parts and produces a comparatively smooth reversal of the motion. The buffers 6 and 7 are also adjustable on the rod 8 to enable them to be set so that the shock on reversal may be partly taken up by them. The best result is obtained when the buffers 10, 11, and 12 are so set with regard to each other that they get the traverse-block 5 slightly "under way" in the reverse direction just before the pinion comes into action, the pinion, so to say, being allowed to follow up the traverse-block. By carefully proportioning the number of teeth

to the bare part of the pinion and suitably setting the buffers a practically instantaneous reversal is obtained of great value in yarn or thread winding machines, particularly those in which yarn is wound on tubes or bobbins without heads, where a very sudden reversal is necessary in order to properly build up the yarn on the tube.

What I claim as my invention, and desire to secure by Letters Patent, is—

1. The combination of a continuously-rotating shaft, a pinion with teeth of graduated lengths, a reciprocating traverse-block, having internal racks with teeth of graduated lengths, and buffers for minimizing shock and assisting the reversal of the reciprocating motion substantially as and for the purpose set forth and shown.

2. The combination of a reciprocating traverse-block, parallel opposed racks and an intervening driving-pinion, the said racks and pinion having the teeth where they first engage of progressively varying lengths substantially as and for the purpose set forth and shown.

3. The combination with a reciprocating traverse-block, operated by opposed racks, and an intervening continuously-rotating driving-pinion, of buffers rotatable on axes secured on the traverse-block and a buffer rotatable on an axis secured on and revolving with the pinion substantially as and for the purpose set forth and shown.

In witness whereof I have hereunto set my hand in the presence of two witnesses.

JAMES HORROCKS.

Witnesses:

JOHN HALL,

ALFRED T. WHITLOW.
